Attorney

UNITED STATES PATENT OFFICE.

GEORGE M. LOWE, OF BOWEN, COLORADO.

SAFETY STATION FOR SUBTERRANEous PASSAGEWAYS.

Application filed September 7, 1921. Serial No. 498,955.

To all whom it may concern:

Be it known that I, GEORGE M. LOWE, a citizen of the United States, residing at Bowen, in the county of Las Animas and 5 State of Colorado, have invented certain new and useful Improvements in Safety Stations for Subterranean Passageways, of which the following is a specification, reference being had to the accompanying drawings.

This invention relates to safety stations for subterranean passageways and has relation more particularly to a station designed for use within the passageway or gallery of 15 a coal mine or the like, and it is an object of the invention to provide a station of this general character having novel and improved means whereby the occupants thereof may be supplied with fresh air and water and 20 may also have communication exteriorly of the mine.

Another object of the invention is to provide a novel and improved station of this general character which is particularly desirable for use after a mine explosion and 25 which is so arranged as to be free of pressure and which includes a normally closed exit whereby ingress of gases or the like within the chamber is prevented.

30 An additional object of the invention is to provide a station of this general character having novel and improved means whereby a supply of fresh air may be circulated therein, together with means whereby the 35 air may be prevented from discharging within the station should necessity require.

The invention consists in the details of construction and in the combination and arrangement of the several parts of my improved safety station for subterranean passageways whereby certain important advantages are attained and the device rendered simpler, less expensive and otherwise more convenient and advantageous for use, as will 45 be hereinafter more fully set forth.

The novel features of my invention will hereinafter be definitely claimed.

In order that my invention may be the better understood, I will now proceed to describe the same with reference to the accompanying drawings, wherein:

55 Figure 1 is a diagrammatic view of a mine having arranged therein stations constructed in accordance with an embodiment of my invention;

Figure 2 is a vertical sectional view taken through one of the cabins or chambers; and

Figure 3 is a horizontal view taken through one of the cabins or chambers.

As disclosed in the accompanying drawings, G denotes a mine gallery or passageway having branching therefrom the entries E in communication with which are the mining or working rooms R.

Each of the entries E at a point preferably in relative close proximity to the gallery or passageway G is provided with a station S, said station including a cabin or chamber 1 of desired dimensions and an entranceway 2 leading from the entry E. The 70 cabin 1 and entranceway 2 are cut out of the coal or other formation forming a wall of the entry E and said cabin 1 and entranceway 2 have the walls thereof lined with a layer of cement, preferably of a thickness of 75 six inches. By having the cabin 1 and the entranceway 2 cut in the wall of an entry E, the same are positioned or located to be free of the force or pressure created by an explosion within the mine. 80

The entranceway 2 is substantially elongated and preferably of a length of about six feet and associated with each end portion of the entranceway 2 is a swinging door 3. The doors 3 are normally maintained 85 closed through the action of the springs 4 or their equivalent. By this arrangement of the doors 3, one of said doors will be closed when the other is opened.

To prevent the entrance of gases or the 90 like within the cabin 1 through the entranceway 2, the marginal portions of each of the doors 3 are stepped, as at 5, the abutting or coacting portions of the entranceway 2 being similarly stepped, as at 6. 95

In addition to the regular fan house H exteriorly of the mine for maintaining the desired ventilation within the mine, I also provide an additional fan house F exteriorly of the mine. Leading from the fan house 100 F to one of the cabins 1 is an air pipe line 7, said pipe line being laid under ground and covered. The pipe line extends upwardly and vertically within the cabin 1 through the floor thereof and the outlet or 105 ejection end of the pipe, within the cabin 1, is normally open.

The cabins 1 within the mine, and more particularly the cabins associated with the gallery, are connected in series by an air 110

pipe line 8, said pipe line 8 within the first cabin 1 being vertically disposed through the bottom of said cabin in relatively close proximity to the delivery end of the pipe line 7, while the opposite or delivery end of the pipe line 8 in the succeeding cabin, and which delivers within said cabin, is also vertically disposed within the cabin through the bottom thereof and in relatively close proximity to the vertically disposed receiving end portion of the next air pipe line. The pipe line 8 leading from the last cabin 1 of the series is continued under ground and in communication with the atmosphere and preferably exteriorly of the mine. With the fan house F in operation, a circulation of fresh air is maintained within all of the cabins 1.

Should it be found that the supply of fresh air to a cabin 1 is in excess of the necessary requirements, the adjacent end portions of the pipe lines 8 or the pipe line 7 and the adjacent pipe line 8 may be coupled or connected by a pipe line section 9, preferably U-shaped in form. With a section 9 in applied position, it will be understood that the air will be continued beyond the cabin and will not be discharged therein.

Leading from a suitable source of fresh water supply and at a point preferably exteriorly of the mine, is a water pipe line 10, said line being preferably arranged under ground and covered. This pipe line underlies all of the cabins 1 and is provided with the stands 11, each of the cabins 1 having one of said stands extending therein through the bottom thereof. The stand 11 within each of the cabins 1 is provided with a valve or faucet 12 so that the occupants of the cabin may readily obtain drinking water when necessary.

Arranged within each of the cabins 1 is a telephone set 14, the wires 15 of said set extending to a station exteriorly of the mine and preferably through the air pipe lines 7 and 8. Although not necessary, it is preferred that the various telephone sets 14 within all of the cabins 1 be arranged in series.

While the various pipe lines will preferably follow the course of the gallery and entries, yet in the event a cabin is opposed or in close proximity to a cross-cut C, an air line 8, together with the pipe line 10, may be carried through said cross-cut.

In the event of an explosion within the

mine, the persons physically able after such explosion will make their way to one of the cabins 1 and while therein are effectively protected against the pressure resulting from the explosion and also against the resultant gases, fire damp and also effectively protected against a washout. While within the cabins, the occupants are supplied with requisite fresh air and can also have communication exteriorly of the mine. By maintaining within each of the cabins supplies for first aid, such as a pulmotor, bandages and the like, any of the injured persons may receive requisite treatment, and should a supply of food be maintained in each of the cabins, the occupants can live therein with safety for a considerable period of time so that full opportunity is given to a rescue party to reach them.

While I have hereinbefore stated that the various pipe lines are under ground and covered, yet, if preferred, they may be arranged in a trench as this has been found to safeguard the pipe lines against damage.

From the foregoing description it is thought to be obvious that a safety station for subterraneous passageways constructed in accordance with my invention is particularly well adapted for use by reason of the efficiency with which it may be employed, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

A safety station for a subterraneous passageway including a chamber formed within a wall of said passageway and an entranceway leading from said chamber to the passageway, means for closing the entranceway, an induction line for air discharging within the chamber, an air eduction line in communication with the chamber, and a removable coupling engageable within the chamber with the induction and eduction lines for connecting said lines to permit a direct flow from the induction to the eduction line.

In testimony whereof I hereunto affix my signature.

GEORGE M. LOWE.
